ULYSSES S. SMITH, OF SACRAMENTO, CALIFORNIA, ASSIGNOR OF ONE-HALF TO A. C. KAUFMAN, OF SACRAMENTO, CALIFORNIA.

AUTOMATIC CURRENT CUT-OFF FOR ELECTRIC APPLIANCES.

1,101,575.

Specification of Letters Patent. Patented June 30, 1914.

Application filed July 31, 1913. Serial No. 782,368.

To all whom it may concern:

Be it known that I, ULYSSES S. SMITH, a citizen of the United States, residing at Sacramento, in the county of Sacramento, 5 State of California, have invented certain new and useful Improvements in Automatic Current Cut-Offs for Electric Appliances; and I do declare the following to be a full, clear, and exact description of the same, such 10 as will enable others skilled in the art to which it appertains to make and use the same, reference being had to the accompanying drawings, and to the characters of reference marked thereon, which form a part of 15 this application.

This invention relates to improvements in electrical appliances and is particularly designed for the purpose of automatically cutting off the current connection with the appliance whenever the appliance becomes overheated to such a degree as to render it liable to set a conflagration.

Electric heating irons, toasters, electric motors for vehicles and in fact all electrical heating appliances are sometimes carelessly left connected with the current and in due time become overheated to such a degree as to render them extremely dangerous and it is the aim of my invention to provide a 20 means to overcome this by breaking the current connection.

In the accompanying drawings I show the application of the device to an electric heating iron; but of course it may be applied 25 equally as well to other electrical appliances.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a side elevation of the complete electric heating iron with the handle 50 partly broken out and in section. Fig. 2 is a top plan view of the heating iron. Fig. 3 is a perspective view of the fusible plug and connecting rod adapted to be connected with the connecting plug controlling member. Fig. 4 is a top plan view of a supporting

plate attached to the rear end of the heating iron and adapted to receive the rod and plug shown in Fig. 3.

Referring now more particularly to the characters of reference on the drawings, the 60 numeral 1 designates the heating iron and 2 is the heating ring or plate thereon.

The numeral 3 designates the handle of the device, the numeral 4, the plug receiving socket and the numeral 5 is the connecting 65 plug having the usual wires 6 wrapped around the pin 21 in the usual manner.

My improved device consists first of a suitable band spring 7 secured to the handle 3 as at 8 and lying flush with said handle 70 and shaped to conform to the shape of said handle in order that it will not be in the way during the operation of the iron. This band spring 7 has on its outer end a ring 9 normally aligned with the socket 4 and of 75 such shape as to permit the plug to be inserted therethrough with the ends of the pin 21 normally projecting over said ring. On the outer end of the ring 9 is a projecting 80 teat 10 of any suitable shape flexibly connected with which is a ring 11 having a downwardly projecting rod 12 provided with an inwardly projecting bent end 13. The said rod 12 normally projects through a slot 14 in a curved-plate 15 secured to the 85 rear of the iron 1 and a fusible block 16 is secured on the end 13 by means of a hole 17 and this block 16 projects against the heating ring 2 and normally engages the under 90 side of the plate 15 to hold the rod 12 in 95 its normal position as shown in Fig. 1, which holds the spring 7 in normal position in the handle 3. When the ring 2 becomes overheated, the block 16 breaks releasing itself from the bent end 13 and then the

force of the spring 7 pulls the rod 12 out of engagement with the slot 14 and up through an open space 20 in the under side of the plate 15 and through a hole 19 in the top of said plate 15. This action of the spring 7 100 will also, by reason of the engagement of the ring 9 with the pin 21, pull the plug 5 out of the socket 4, thus breaking the electric circuit and stopping the further heating of the iron. Then another plug 16 may be 105 inserted on the bent end 13 and the parts returned to normal position each time, as desired.

From the foregoing description it will readily be seen that I have produced such a 110

device as substantially fulfills the objects of the invention as set forth herein.

While this specification sets forth in detail the present and preferred construction of the device, still in practice, such deviations from such detail may be resorted to as do not form a departure from the spirit of the invention.

Having thus described my invention what I claim as new and useful and desire to secure by Letters Patent is:

1. A device of the character described comprising the combination with a heating appliance having a removable plug, of a spring member secured on said appliance, a ring on said spring member, said ring normally receiving said plug and engaging a projecting pin on said plug, means for holding said spring normally inactive and means for putting said spring member into

action when said appliance becomes heated to a predetermined degree, as described.

2. A device of the character described comprising the combination with a heating appliance having a removable connecting plug, of a spring controlled member receiving said plug, a slotted member on said appliance, a rod connected with said spring member and projecting through the slot of said slotted member, and a fusible block secured on the end of said rod and normally engaging said appliance and said slotted member, as described.

In testimony whereof I affix my signature in presence of two witnesses.

ULYSSES S. SMITH.

Witnesses:

C. H. S. BIDWELL,
R. PLATNAUER.
